UNITED STATES PATENT OFFICE

FRED E. BEARDEN, OF SPARTANBURG, SOUTH CAROLINA

METHOD OF MANUFACTURING FLEXIBLE HEADS FOR MOPS, DUSTERS, AND BRUSHES

Application filed November 22, 1929. Serial No. 409,060.

This invention relates to a method of manufacturing a flexible head for mops, dusters, brushes, etc., and the invention has for its object to provide, in a manner as hereinafter set forth, a mop, duster, or brush head including a group of flexible, closely arranged, radially disposed, looped head members anchored at their inner ends.

A further object of the invention is to provide, in a manner as hereinafter set forth, a flexible mop, duster or brush head including a flexible group of closely arranged, looped, radially disposed, freely movable head members extended from and having their inner ends connected to a resilient carrier and with the latter inherently acting to clamp the inner ends of the head members therewith.

A further object of the invention is to provide, in a manner as hereinafter set forth, a flexible mop, duster or brush head including a coiled resilient carrier and a series of looped, freely movable, radially disposed, flexible head members interlaced with the carrier and having their inner ends tightly clamped between the coils of the carrier whereby said inner ends are anchored stationary.

A further object of the invention resides in the production of a flexible head for mops, brushes, dusters, etc., by the interlacing of successive parts of one or more continuous flexible strands with a normally extended, coiled, resilient carrier to provide a group of vertically disposed, closely arranged, radially extending, looped, freely movable, flexible head members extended from the carrier and then providing for the contraction of the carrier to fixedly clamp between the coils thereof the inner ends of said members whereby such inner ends are anchored stationary to the carrier.

As illustrating one form of a device capable of carrying out the method in accordance with this invention to produce a flexible mop, duster or brush head and further illustrating flexible heads produced in accordance with this invention and the adaptation of such heads for their respective use

reference is had to the accompanying drawings.

In the drawings:

Figure 1 is a top plan view of the device.

Figure 2 is a side elevation partly in section. 55

The method, in accordance with this invention for producing a flexible mop, duster or brush head consists in providing a resilient carrier of the coiled type. The carrier, 60 during the carrying out of the method is extended lengthwise to space the coils thereof. The carrier is held in extended position until the head members are completed. Each of the head members is in the form of a 65 flexible, freely movable loop of the desired length. One or more continuous strands of flexible material, such as cotton yarn or other suitable material is employed to provide the head members. The head members are 70 formed from successive parts of the length of the strand or strands. 76

The length of the head members can be as desired. The length of the head members is provided for by posts arranged in 75 spaced relation and surrounding the carrier. The length of the head members being decided upon the posts are spaced a distance from the carrier corresponding to the desired length of the head members. A row 80 of spaced posts are employed and the posts spaced the desired distance from each other. Preferably the posts are arranged in a circular row and are spaced equi-distant from each other and also spaced equi-distant from 85 the carrier. It is to be understood however that the posts can be arranged any desired distance from each other and also any desired distance from the carrier and also can be set up in a row other than circular. 90

The strand or strands is or are interlaced with the carrier by passing it around the coils of the latter and then around the posts. The interlacing is had when the coils of the carrier are extended. The interlacing of the 95 strand or strands with the carrier starts from one end of the latter and can be carried on throughout the carrier, that is to say to the other end thereof, but the interlacing can be had from one end of the carrier to a point 100

removed from the transverse median thereof, then omitting the interlacing of a plurality of coils and then continuing the interlacing to the other end of the carrier whereby the 5 central coils of the carrier will be free of head members. The head members are in the form of endless loops, one end thereof being around a coil of the carrier and the other end being free after removal from the post. The head 10 members are arranged in sets, and with the members of each set opposing each other in close relation. The number of sets of looped head members can be as desired. The sets are radially disposed with respect to the car- 15 rier.

After the strand or strands have been interlaced with the carrier, the latter is released providing for the contraction thereof and under such conditions the inner ends or bights 20 of the head members are tightly clamped by and between the coils of the carrier, under such conditions the carrier possesses inherent means for anchoring the inner ends of the head members stationary.

25 Referring to the drawings 1 indicates a base provided with a circular row of vertical posts 2 of a height corresponding greater than the coiled carrier 3 when the latter is in extended position. The carrier 3 is detach- 30 ably secured to the base 1 and is shown in an extended position. The reference character 4 indicates the looped, freely movable, flexible head members which are provided by the interlacing of the strand with the carrier 3. 35 The inner ends of the members 4 are indicated at 6 and the outer ends at 7. The inner ends surround the coils of the carrier 3 and the outer ends surround the posts 2. Preferably a continuous strand will be employed 40 for setting up each set of flexible, freely movable, closely arranged, looped head members. It is to be understood however that the strand or strands can be of a length to provide one or more sets of head members. The carrier 45 3, shown in Figure 1, is permitted to contract before the members 4 are removed from the posts 2. The posts provide formers.

It is thought the many advantages of a method in accordance with this invention for 50 producing flexible heads for mops, dusters, brushes, etc., as well as the product derived from such method, can be readily understood, and although the preferred embodiment of the invention and the product is as illustrated 55 and described, yet it is to be understood that changes in the details thereof can be had which fall within the scope of the invention as claimed.

What I claim is:—

60 1. A method of manufacturing a flexible head for mops, brushes and dusters comprising the extending of a coiled, contractile carrier, tensioning said carrier in extended position, training successive portions of a flexible 65 member around the coils of the carrier to

provide flexible, closely arranged, looped members, removing the tension from the carrier to permit it to retract to clamp between the coils thereof the inner bights of said members.

2. A method of manufacturing a flexible head for mops, brushes and dusters comprising the extending of a coiled, contractile, carrier, tensioning said carrier in extended position, training portions of one or more 70 flexible members around the coils of the carrier to provide radially disposed sets of opposed, flexible, closely arranged, looped members, removing the tension from the carrier 75 to permit it to retract to clamp between the coils thereof the inner bights of said members.

In testimony whereof, I affix my signature hereto.

FRED E. BEARDEN.
